KEY ENVELOPE AND METHOD OF MAKING THE SAME

Application filed April 27, 1928. Serial No. 273,421.

It is the present practice for banking institutions to lease what are termed "deposit boxes", to wit, small drawers provided with locks, which may be opened by keys furnished to the lessees. Despite the usual precautions, it is possible that such boxes may be fraudulently opened by any employee of the lessor who has had access to the keys before the delivery of the same to the lessee, and thus had an opportunity of making, or having made, a duplicate or duplicates of the same.

Therefore, the principal object and effect of my invention is to provide an envelop with means so constructed and arranged that it may be utilized to seclude any such original key, from the time of its manufacture until its delivery to the lessee.

It is the usual practice, and is desirable, to store such keys in racks comprising compartments but slightly larger than the shanks of two similar keys which are furnished with each lock for the use of the lessee. Therefore, it is a further object and effect of my invention to provide an envelop which may be used to seclude such a pair of keys together and in such manner as not to interfere with the storage and removal of such key packages with respect to such racks.

In the preferred form of my invention hereinafter described, such an envelop includes a seamless tube of flexible material, fitting over the shank portions of the keys which are provided with the biting notches for the lock tumblers; said tube being slit or slotted longitudinally at one end, so that opposite side walls thereof may extend upon opposite faces of the key handles; such extensions being perforated in registry with a hole in the handle of the key, thus adapted to be connected by a fastening member extending through the key and secured upon opposite sides of the envelop. Such a fastening member may be an eyelet, or other form of rivet.

Although such secluding means is in no sense "burglar-proof", it is of such character

as to manifest if any attempt has been made to open it, and the fact that it has not been tampered with affords assurance to the lessee that no unauthorized person has had an opportunity of making a duplicate of the key or 50 keys thus secluded.

My invention includes the various novel features of construction, arrangement and method of manufacture hereinafter more definitely specified.

In said drawings; Fig. I is a plan view of a package including a pair of keys in a seamless tube in its normal sealed condition.

Fig. II is an edge view of said package shown in Fig. I.

Fig. III is a plan view, similar to Fig. I, but showing an envelop formed of a primarily plane sheet of metal punched and folded to tubular form.

Fig. IV is an edge view of the key package shown in Fig. III.

Fig. V is a plan view of the sheet blank from which the envelop shown in Figs. III and IV is formed.

Fig. VI is a perspective view of an envelop formed of primarily plane sheet material similar to that shown in Figs. III and IV, but with its edges interlocked.

Fig. VII is a perspective view of a seamless tube showing the method of forming 75 therefrom envelops such as are shown in Figs. I and II.

Fig. VIII is a fragmentary sectional view, taken on the line VIII, VIII in Figs. III and IV, but showing a modified form of fastening means.

Referring to the form of my invention shown in Figs. I and II; the pair of keys are precisely alike, each having a shank 1 with bittings 2 along one edge thereof and a handle 3 at one end thereof, with an opening 4 therethrough. Said keys are conveniently placed with their bittings extending in opposite directions and with their shanks fitted in the envelop 6, which is a seamless tube of 80

metal, celluloid or other suitable material, preferably of a flexible nature. Said tube 6 is slotted so as to remove its opposite edge walls, as indicated at 7, and leave its opposite 5 side walls extend upon opposite faces of the key handles; such extensions, indicated at 8, being perforated at 9 in registry with the holes in the handles of the keys, to receive the fastening member 10 which is an eyelet 10 having flanges 11 and 12 extending upon opposite sides of the envelop which is thus securely fastened in such relation with the keys as to exclude and conceal the bittings 2 thereof until said eyelet is removed to permit removal 15 of said envelop and release of the keys.

Such envelops 6 as shown in Figs. I and II, may be formed of a seamless rectangular tube of thin brass, copper, aluminum, celluloid or vulcanized fibre 13, as indicated in 20 Fig. VII; said tube being punched and severed at suitable intervals as indicated. However, as indicated in Figs. III, IV, and V, an envelop 14 may be formed of primarily plane blanks 15 punched from any suitable 25 sheet material and bent from the form shown in Fig. V to the form shown in Figs. III and IV, in which form it may be connected with the pair of keys 16 by the eyelet 17, similar to the eyelet 10.

30 Of course, such fastening members 10 and 17 are merely tubular rivets, and it is to be understood that solid rivets may be employed in lieu thereof. However, instead of forming the fastening means as a separate piece 35 subsequently connected with the envelop, I may form cup-shaped projections 19 on the envelop extensions 20, as indicated in Fig. VIII, pressed to such form that they extend in the holes 4 in the keys into contact with 40 each other and may then be spot welded together, at 21, to thus connect the opposite side walls of the envelop through the keys and prevent removal of the latter from the envelop until such fastening means is disrupted.

45 However, the form of my invention wherein the fastening member is distinct and separable from the envelop structure, is advantageous in that such a fastening member having its ends outwardly flanged to larger diameter than the perforations in the key handles through which it extends, may be used to retain the pair of keys in coupled relation, after the envelop is removed, and until such fastening member is disrupted and removed.

50 Therefore, I do not desire to limit myself to the precise details of construction, arrangement or method of manufacture herein set forth, as it is obvious that various modifications may be made therein without departing from the essential features of my invention, as defined in the appended claims.

I claim:

1. The combination with an envelope comprising a tube adapted to fit over and seclude

the bitted shank of a key; of a fastening member separate from said envelop, adapted to extend thru a hole in the key, and comprising an eyelet having its opposite ends extending through the opposite walls of said envelop 70 and riveted exterior thereto; whereby the bittings upon said key are concealed and secluded until said envelop or said fastening member is disrupted and said tube removed.

2. The combination with a key comprising 75 a bitted shank and a perforated handle; of a tubular eyelet extending through said perforation; and an envelop, including a tubular portion fitted over said key shank and concealing the bittings thereof, and 80 having perforated members extending upon opposite sides of said handle in engagement with said eyelet; said eyelet being riveted at its opposite ends exterior to said envelop members; whereby the bittings of said 85 key are secluded and concealed until the connection between said eyelet and envelop is disrupted and said envelop removed, or said envelop is disrupted.

3. The combination with a pair of keys, 90 each comprising a bitted shank and a perforated handle; the perforations in said handles being registered; of a rivet member extending through said perforations; and an envelop, including a tubular portion fitted over 95 the shanks of both said keys, holding them in alinement, and concealing the bittings thereof, and having perforated members respectively extending parallel with the outer faces 100 of the respective key handles and in engagement with said rivet member; said rivet member having outwardly extending flanges at 105 respectively opposite ends thereof overhanging and securing said envelop members; whereby the bittings of said keys are secluded and concealed until the connection between 110 said rivet member and envelop is disrupted, and said envelop removed, or said envelop is disrupted and said keys are retained in coupled relation, independently of said envelop, until said rivet member is disrupted.

4. The combination with a safety deposit box key, comprising a bitted shank and a perforated handle; of a rivet extending through the perforation of said handle; and an envelop inclosing said key and having perforations in its opposite walls engaging said rivet; said rivet having flanges at its opposite ends overhanging the opposite walls of 115 said envelop and securing said key therein; whereby the bittings of said key are concealed until the connection between said envelop and rivet is disrupted, and said envelop removed, or until said envelop is disrupted.

5. The combination with a pair of safety deposit box keys, each comprising a bitted shank and a perforated handle; of a rivet extending through the perforations in said handles; and an envelop inclosing said keys and having perforations in its opposite walls en- 125 130

gaging said rivet; said rivet having flanges at its opposite ends, larger than said perforations, and overhanging the opposite walls of said envelop and securing said keys therein; whereby the bittings of said keys are concealed until the connection between said envelop and rivet is disrupted, and said envelop removed, or until said envelop is disrupted; and said keys are retained in coupled relation, independently of said envelop, until said rivet member is deformed, to permit it to escape through the key perforation.

In testimony whereof, I have hereunto signed my name at Philadelphia, Pennsylvania, this twenty-fourth day of April, 1928.

ARTHUR E. PAIGE.
